Continuation of application Serial No. 141,909,
February 2, 1950. This application December
12, 1951, Serial No. 261,302

6 Claims. (Cl. 260—631.5)

1

This application is a continuation of our ap-
plication, Serial No. 141,909, filed February 2,
1950, now abandoned.

This invention relates to the manufacture of
terpineol from turpentine wherein the interme-
diate product, terpinol hydrate, is dehydrated to
a predetermined controlled extent.

An oil of high terpineol content may be de-
rived from partially refined or purified sulphate
turpentine, gum spirits, steam distilled wood tur-
pentine or other terpene hydrocarbons. Natural
pine oil also contains terpineol as its chief con-
stituent. Consequently, the product of this in-
vention may be considered as a synthetic pine
oil. It may be further purified to a high purity
terpineol by well known methods such as vacuum
fractionation.

The principal object of this invention is to pro-
vide a simplified and more economical method of
producing terpineol by introducing a turpentine-
acid mixture directly into an alkaline solution to
form a slurry of crude terpinol hydrate in a salt
solution within a controlled range of acidity
whereby a high yield of oil of high terpineol con-
tent may be formed by boiling said slurry and
recovering the oil by steam distillation.

Another object of the invention is to produce
an oil of high terpineol content from terpinol
hydrate.

Another object is to provide a process for de-
hydrating terpinol hydrate by means of acid cat-
alysts in the presence of their salts.

A still further object is to provide means for
employing a higher degree and wider range of
acid concentrations in the partial dehydration of
terpinol hydrate in the process of producing ter-
pineol.

Other objects of the invention will be apparent
from the description which follows and from the
appended claims.

This invention relates to a process for produc-
ing terpineol from turpentine, said process com-
prising treating turpentine with an acid to form
a mixture of crude terpinol hydrate, by-products
and acid, terminating the treatment approxi-
mately when the viscosity of said mixture reaches
its maximum by partially neutralizing the mix-
ture of acid and addition products by introducing
said mixture into an alkaline solution, the alka-
linity of the solution being controlled to provide
an acidity of the resulting slurry just sufficient
to dehydrate the crude terpinol, dehydrating said
terpinol by boiling said slurry and forming crude
terpineol, and simultaneously recovering said
crude terpineol by steam distillation.

2

The novel features of the invention may be
conveniently shown by comparison of the follow-
ing descriptions of the conventional process and
of the process of this invention.

5 In the accompanying drawings which form a
part of this specification:

Fig. 1 is a flow sheet for a conventional proc-
ess for producing terpineol from turpentine,

Fig. 2 is a graph showing the yield of terpineol
10 as against the normality of sulphuric acid in
spent liquor at various Na_2SO_4 concentrations,
and

Fig. 3 is a flow sheet for this new process for
producing terpineol from turpentine.

15 A typical conventional process for producing
terpineol comprises a series of time and labor
consuming steps illustrated by the flow sheet
shown in Fig. 1.

The first step of the conventional process con-
sists in treating the turpentine with acid, for
example, sulfuric acid of a concentration of
about 60% at a temperature in the range of
0°—5° C. for several hours to form an addition
compound which dissolves in the acid.

20 25 The 2d step consists in diluting this mixture
by introducing it into a sufficient quantity of
cold water to reduce the acid concentration to
about 20%—30% H_2SO_4 . The mixture is agitated
during dilution, the acid-turpentine addition
product quickly hydrolyzing to form a slurry of
30 crude terpinol hydrate and oily by-products in
the dilute acid.

An alternate method of carrying out the 1st
and 2d steps described is to treat the turpen-
tine under agitation with more dilute acid, for
example, 25% sulfuric acid for several days. In
this case the addition compound is presumably
formed and slowly hydrolyzed forming terpinol
hydrate and oily by-products in one step but at
40 the expense of vastly increased time of reaction.

In the 3d step, the crude terpinol hydrate is
removed from the dilute acid by centrifuging,
along with a considerable portion of the oily by-
products.

45 50 In the 4th step the damp centrifuged terpinol
hydrate, still containing some acid, is neutralized
with a solution of an alkali such as sodium car-
bonate to remove the residual acidity.

In the 5th step the terpinol hydrate is thor-
oughly washed with water. The terpinol hydrate
is now in a partially purified state but still con-
tains small quantities of the by-product oils, and
unless the washing has been extremely thorough,
will still contain traces of the alkali.

55 In the 6th step the partially purified terpinol

hydrate is partially dehydrated by boiling in the presence of a dilute acid catalyst such as H_2SO_4 of a concentration in the range of about 0.2 N to 0.5 N, forming crude terpineol, which is simultaneously removed from the reaction vessel by steam distillation.

The oil thus obtained is of a fair degree of purity, having for example, a terpineol content of 85% to 90%, and a yield of 50% to 55% by weight on the weight of the turpentine treated. The actual terpineol content is about 42% to 49% by weight based on the weight of the turpentine.

The by-product oil removed from the slurry of crude terpinol hydrate by centrifuging in the third step of the process, contains appreciable quantities of terpineol. Since this by-product oil may constitute 30% to 35% by weight of the turpentine treated and contains some terpineol, an addition to the yield of terpineol may be obtained by separately treating it, though at a considerable added operating expense.

To obtain this additional yield, the by-product oil is steam distilled to separate the nonvolatile polymers and remove traces of acid. The volatile fraction of the by-product oil may amount to about 25% by weight of the turpentine and contain 30% to 32% of actual terpineol, so that 7.5% to 8% additional terpineol may be recovered by this additional step.

This oil may then be fractionated to obtain an oil of higher terpineol content, if so desired.

Thus the best overall yield of crude terpineol comprising the direct recovery plus the returns from steam distilling the by-product oil that may be expected from the conventional process amounts to about 75% to 80% by weight based on the turpentine, and the yield of actual terpineol is about 49% to 56% by weight based on the turpentine.

Among the disadvantages of a typical conventional process are the following:

1. It involves a multiplicity of steps including a relatively high labor and processing cost.

2. A difficult operating problem consists in the disposal of the dilute acid centrifuged from the crude terpinol hydrate.

3. An appreciable quantity of terpinol hydrate remains dissolved in the dilute acid, thus lowering the yield substantially.

4. The by-product oil, which is also centrifuged from the slurry of crude terpinol hydrate and acid, contains terpineol which is lost unless the by-product oil is separately treated for recovery of such terpineol.

5. When the partially purified terpinol hydrate is partially dehydrated to form terpineol, the acidity must be controlled accurately within a rather narrow range, since any marked rise in the acidity above the range previously mentioned will completely dehydrate the terpinol hydrate and form undesirable hydrocarbons. By reference to curve A of Fig. 2, the effect of very small variations in the acidity of the slurry on the yield of terpineol is evident. For example, at 0.2 N H_2SO_4 , the terpineol content is about 72.5% while at 0.4 N it falls to about 58%, and above that acidity, falls rapidly to still lower percentages. In practice, therefore, the acidity must be controlled within quite low limits in order to obtain an oil of even fair quality.

This critical control of the acidity imposes a difficult operating problem requiring a high degree of skill, care and vigilance. Furthermore, the crude terpinol hydrate may be contaminated

with unknown quantities of acid or alkali so that a further difficulty arises in accurately adjusting the acidity of the very dilute treating solution initially.

5 One way of increasing the yield of terpineol is to use the conventional process shown in Fig. 1 and hereinbefore described up to the point of dehydration, and then add a salt of an acid catalyst.

10 The conversion of terpinol hydrate to terpineol involves the removal of one of the two tertiary hydroxyl groups from the terpinol hydrate molecule to form an ethylenic linkage. This may be accomplished by boiling the terpinol hydrate in dilute solutions of mineral acids, organic acids, certain salts, etc.

15 The usual commercial method of effecting the conversion as hereinbefore described is to treat the terpinol hydrate at atmospheric boiling temperature with dilute sulfuric or phosphoric acid. Generally, unless the concentration of acids is accurately controlled initially and throughout the dehydration cycle to relatively low concentrations, the reaction proceeds with great 20 rapidity, is difficult to control and results in an oil containing a relatively low percentage of terpineol contaminated with excessive quantities of terpene hydrocarbons.

25 For example, when sulfuric acid is used as a dehydrating agent, the acid concentration must not exceed approximately 0.5 N to avoid excessive and undesirable dehydration of the terpinol hydrate. On the other hand, as the concentration is reduced it becomes increasingly difficult to accurately control and the rate of reaction is progressively reduced and finally proceeds so slowly as to be commercially impractical. Thus to obtain even fair yields of terpineol, the industry is faced with the extremely difficult practical 30 problem of accurately controlling the H_2SO_4 concentration within low, narrow limits, not in any event exceeding about 0.5 N.

35 By reference to Fig. 2, the significance of control of the concentrations of acids on the purity of terpineol is illustrated by the steep character of curve A. For example, at 0.1 N, the purity of the oil is about 81%; at 0.2 N, about 72%, while at 0.4 N it falls to 58% or 59%. Above the higher concentration it will be observed that the purity 40 falls off so rapidly as to prohibit the use of higher concentrations.

45 Following is an example of the conventional process:

EXAMPLE 1

50 150 grams of chemically pure terpinol hydrate were boiled with 1000 milliliters of 0.405 N sulfuric acid, the oil was continuously removed from the reaction mixture by steam distillation. 115 grams of product were obtained, having an actual terpineol content of 59.0%. The yield of crude terpineol by weight was 76% of the weight of the terpinol hydrate, while the yield by weight of actual terpineol based on the weight of the terpinol hydrate was 45%.

55 We have discovered that the extremely high reactivity of acid catalysts in the dehydration process may be substantially inhibited and a considerably higher and wider range of acid concentrations employed by carrying out the reaction in the presence of salts of the acids employed. For example, with the use of a sodium sulphate solution, a sulfuric acid concentration of 1.5 N will result in an oil containing about 85% terpineol. 60 By reference to curve B of Fig. 2 it will be seen 65

that the presence of sodium sulphate gives oils of terpineol content of 80% to as high as 96% to 97%. Such higher acid concentrations are far easier to control and furthermore with the use of the salts of the acids, no such extremely accurate adjustment of acidity is required such as is typical of the conventional processes.

Our discovery therefore permits the production of terpineol of much more highly refined quality than is obtainable with the conventional processes.

The following examples illustrate the improvement in yield and quality of terpineol resulting from the use of various acid catalysts in the presence of a salt of the acid employed, or salts other than the salt of the acid employed.

EXAMPLE 2

150 grams of chemically pure terpinol hydrate were boiled with 1000 milliliters of 1.04 N sulfuric acid in which 250 grams of sodium sulphate were dissolved. The terpineol was continuously removed from the reaction mixture by steam distillation. 121 grams of product were obtained which contained 92.8% actual terpineol.

The yield of crude terpineol by weight was 81% of the weight of the terpinol hydrate, while the yield by weight of actual terpineol based on the weight of the terpinol hydrate was 75%.

EXAMPLE 3

50 grams of terpinol hydrate were boiled with 1000 milliliters of 0.57 N phosphoric acid containing 263 grams of saltcake. (95% Na_2SO_4 .) The oil formed was continuously removed by steam distillation. The yield of oil was 40 grams, analyzing 98% terpineol.

The yield of crude terpineol was 80% by weight and the yield of actual terpineol 78.4% based on the weight of the terpinol hydrate.

EXAMPLE 4

50 grams of terpinol hydrate were boiled with 1000 milliliters of 1.10 N phosphoric acid containing 263 grams of saltcake. (95% Na_2SO_4 .) The oil formed was continuously removed by steam distillation, the yield being 40 grams analyzing 97% terpineol.

The yield of crude terpineol by weight was 80% and the yield of actual terpineol 77.6% based on the weight of the terpinol hydrate.

EXAMPLE 5

50 grams of terpinol hydrate were boiled in 1000 milliliters of 0.50 N oxalic acid. The oil formed was removed by steam distillation and the yield was 39 grams analyzing 70% terpineol.

The yield of crude terpineol by weight was 78% and of actual terpineol 54.6% based on the weight of the terpinol hydrate.

EXAMPLE 6

50 grams of terpinol hydrate were boiled with 1000 milliliters of 2.01 N oxalic acid containing 158 grams of ammonium oxalate. The oil formed was removed continuously by steam distillation and the yield was 40 grams analyzing 80% terpineol.

The yield of crude terpineol by weight was 80% and the yield of actual terpineol 74.4% based on the weight of the terpinol hydrate.

EXAMPLE 7

50 grams of terpinol hydrate were boiled with 1000 milliliters of 2.02 N oxalic acid containing 250 grams of potassium sulfate. The oil formed

was continuously removed by steam distillation and the yield was 40 grams analyzing 87% terpineol.

The yield of crude terpineol by weight was 80% and the yield of actual terpineol 68.4% based on the weight of the terpinol hydrate.

The new process of this invention imposes no such difficult control problem with respect to acidity in the dehydration step, eliminates several entire steps of the hereinbefore described conventional process and in addition, avoids the losses in yields and the troublesome acid recovery or disposal problem.

This improvement is accomplished by diluting the mixture of turpentine-acid addition product by feeding it directly into a solution of an alkali whereby a salt solution is formed and the acid concentration is reduced to a range such that upon boiling, terpineol of good quality is produced in a high yield.

The alkaline solution may be prepared with soda ash, for example, so that upon introducing the mixture of turpentine-acid, the sodium salt is formed; it may also be prepared with ammonia, NaOH , KOH , K_2CO_3 , etc. Other acids may also be used in the process, for example, phosphoric acid but sulfuric acid is preferred on account of its low cost.

By referring to curve B of Fig. 2, it will be seen that with an aqueous solution of sodium sulphate containing 380 grams of Na_2SO_4 per liter and about 2.0 N with respect to sulfuric acid, the purity of the crude terpineol from terpinol hydrate is about 79% while at an acidity of 0.9 N it rises to 93-94%. Even at a concentration of 2.4 N the purity is 71% or far greater than that which is obtained by the conventional process with 0.4 N (see curve A, Fig. 2). Thus the range of acidity in which a high quality terpineol can be produced is greatly extended when the dehydration is carried out in the presence of salts such as sodium sulphate, and a higher acid concentration may be employed than in the conventional process.

The flow sheet shown in Fig. 3 illustrates the new simplified process, employing sulfuric acid in the initial step and soda ash as the neutralizing agent.

When employing sulfuric acid, which is preferred because of its economy, we have found the best conditions for carrying out the first step of this process are as follows:

A. The highest yields of terpinol hydrate and correspondingly of terpineol, are obtained at weight ratios of sulfuric acid (basis 100%) to turpentine in the range of 1.08 : 1 to 1.80 : 1. Higher ratios up to 2.88 : 1 have been used but without any significant improvement in yield than with ratios in the preferred range. Lower ratios result in lower yields of terpinol hydrate and while the chemical costs are correspondingly lower, in general they are offset by the lower yield of the desired product.

B. Insofar as the yields of terpinol hydrate are concerned, it makes little difference whether the turpentine is added to the acid or vice versa. We prefer to add the turpentine to the acid because the mixture of the two liquid phases is more readily accomplished in this manner and, furthermore, the highest yields of terpinol hydrate are obtained in a shorter time.

C. The time of adding the turpentine to the acid is important only in that it should be held within such limits as to avoid a rise in temperature above about 5° C. The time of addition of

the acids is a function of the refrigeration capacity available. Ordinarily the addition can be completed under satisfactory temperature conditions in from 30 to 45 minutes. If the temperature of the mixture is allowed to exceed about 5° C. the reaction rate is accelerated but the yield is decreased. At temperatures below 0° C. the reaction rate is slowed without any appreciable increase in yield over that obtained within the preferred range of temperature control.

D. Acid concentrations between 55% and 65% may be employed but we prefer to operate within the range of 57% to 62%. At higher concentrations the reaction is faster, the temperature more difficult to control and the yields are lower. At lower acid concentrations the rate of reaction is slower while the yields are not improved.

E. As the reaction between the turpentine and the acid proceeds, the yield of terpinol hydrate increases to a maximum value and then slowly declines. Thus for best results it is desirable to terminate the reaction at, or near, the point of maximum yield. A convenient means for determining the maximum yield point is the viscosity of the reaction mixture. We have found the viscosity to be a reliable index of the progress of the reaction and that the maximum viscosity coincides with the maximum yields of terpinol hydrate. Since the speed of reaction is dependent on the acid concentration and the temperature within the preferred ranges set forth above, the highest yield may be obtained over a considerable variation of the reaction time, usually within 1½ to 3 hours.

The second step in the process comprises the novel method of diluting the mixture of acid and turpentine addition product formed by the treatment of turpentine and acid described in the first step. A solution of an alkali, preferably soda ash, is formed into which the turpentine-acid mixture is added. The solution contains a sufficient amount of soda ash to partially neutralize the resulting mixture and form a slurry of crude terpinol hydrate suspended in a slightly acidic solution of the sodium salt (sodium sulphate when sulfuric acid is used). Solutions of other alkalis may be used, if desired, to form salts of the acid catalyst employed.

The turpentine-acid mixture should be added to the alkali solution rather than vice versa. In this manner the acidity is reduced to a low value so quickly that there is no undesirable effect on the yield of terpinol hydrate. However, since a considerable amount of carbon dioxide, as well as heat is evolved when the turpentine-acid mixture is partially neutralized by the alkali, care must be taken not to carry out the neutralization too rapidly in order to avoid the tendency to boil out the contents of the vessel by too rapid an evolution of carbon dioxide and to prevent overheating the entire mass with consequent formation of hydrocarbons and polymers. It has been found that the addition may be conveniently and advantageously carried out in from 10 to 45 minutes, preferably about 30 minutes.

The quantity of alkali used to partially neutralize the turpentine-acid reaction mixture depends primarily upon the ratio of acid-turpentine used in the first step of the process. The objective is to produce a salt solution, for example, sodium sulphate solution, having sufficient acidity to dehydrate the terpinol hydrate to just the required extent to form crude terpineol and avoid excessive dehydration with resulting undesirable

terpene hydrocarbons and lower yields of terpineol.

We have found that in the presence of concentrated sodium sulphate solution, sulfuric acid concentrations within the range of 0.7 N to 1.6 N are very satisfactory and produce the highest yield of crude terpineol with a minimum quantity of undesirable terpene hydrocarbons. However, concentrations below 0.7 N and above 1.6 N may be used and yield satisfactory results without the difficult problem of control of concentrations of the lower values within very narrow limits inherent in the conventional process on the one hand, or encountering undue or prohibitive decrease in terpineol purity on the other. In fact, concentrations from approximately 0.7 N to 2.6 N may be used.

In the reaction of this step of the process, sodium sulphate is formed as a by-product when H_2SO_4 is used as a catalyst and soda ash as an alkali. Since this material has a wide market for many purposes, including the kraft pulping process from which one of the starting materials for manufacturing terpineol is derived, namely, sulphate turpentine, it is desirable to end the second step of the process with as concentrated a solution of sodium sulphate as possible in order to minimize the evaporation required to recover the sodium sulphate. Consequently the alkaline solution to which the turpentine-acid mixture is added is formed with a minimum quantity of water so as to produce a highly concentrated sodium sulphate end solution. We have found that good results are obtained with a water to soda ash ratio from 2:1 to 1:1. Higher ratios of water may be used but it is uneconomical and in addition, as the sodium sulphate solution is diluted a lower acidity must be used to obtain the same degree of purity of terpineol.

Upon completion of the addition of the reaction mixture to the alkaline solution the slurry is heated to boiling temperature by means of a closed steam coil in the dehydrator whereby the terpinol hydrate is converted to terpineol. The terpineol is removed from the reaction zone by simultaneous introduction of live steam by means of a perforated steam coil, the vapor condensed and the oil and water layers separated by decantation. A preferred example of the process is described as follows:

50 pounds of refined sulphate turpentine were reacted with 57% H_2SO_4 in a molar ratio of 2:1 at 0°-5° C. for 2½ hours.

The resultant mixture was slowly poured into a solution containing 71 pounds of soda ash and 41 pounds of water. This produced a terpinol hydrate slurry in a concentrated aqueous solution of sodium sulphate with an amount of free acid to result in a concentration of 0.72 N.

Upon boiling the solution and removing the crude oil by steam distillation 45.4 pounds of crude terpineol were obtained, which analyzed 74.4% actual terpineol.

The yield of crude terpineol was 91%, by weight, based on the weight of the turpentine treated, or 67.6%, by weight, of actual terpineol on the weight of the turpentine treated.

This yield of crude terpineol of 91% by the process of this invention using 0.72 N concentration of acid in the dehydration step compares with 50% to 55% by the hereinbefore described conventional process. Even when the expensive additional conventional step of recovering the terpineol from the by-product oils is employed,

the best total yield of volatile oils by the conventional process is only about 75% to 80% by weight based on the weight of the turpentine.

Following is a comparison of yields and degrees of refinement of terpineol by the usual and new processes:

Comparison of terpineol yields

[By weight on weight of turpentine]

	Conventional Process	New Process
Crude Terpineol by Direct Steam Distillation.	Percent 50-55	91%.
Terpineol Content of Crude Yield	85-90	74.4%.
Percent Actual Terpineol on Turpentine	42-49	68%.
Steam Volatile By-Product Oil	25	(1)
Percent actual Terpineol in Steam Volatile By-Product Oil	7-8	(2)
Total Steam Volatile Oil Produced	75-80	91%.
Total Percent Actual Terpineol Yield on Turpentine	49-57	68%.

¹ Only one oil product.

² Only one oil produced.

The new process does not involve the steam distillation of two separate oil fractions as described in the conventional process but achieves a direct one step yield of crude oil of good quality considerably greater than realized from the corresponding step of the conventional process. The actual terpineol content of the partially refined product is 20% to 25% greater than from the usual process.

Even including the terpineol which may be recovered by the time consuming and costly additional steam distillation of the by-product oils by the usual process, the actual terpineol content of the oil by the new process is 10% to 20% greater by weight based on the weight of the turpentine.

In addition to the much improved yields of partially refined oil, the new process, comprising essentially but three steps in contrast to at least six separate steps by the usual process (seven including recovery of the terpineol from the by-product oils), is simpler, and results in important economies in time, labor and materials.

Following is an example of the use of phosphoric acid in the process of this invention:

270 grams of refined sulphate turpentine were reacted with 460 grams of 85% phosphoric acid at 0°-5° C. for 2½ hours.

The resulting turpentine-acid mixture was slowly introduced into 1000 milliliters of an ammonium hydroxide solution containing 130 grams of ammonium hydroxide. The resulting slurry of terpinol hydrate contained sufficient free phosphoric acid to give an acid concentration of approximately 5 N.

The slurry was boiled and the crude terpineol removed by steam distillation. Small increments of phosphoric acid were added during the distillation to increase the rate of formation of terpineol so that the final acid concentration was about 8.0 N and the final ammonium phosphate concentration approximately 125 grams per liter.

231 grams of crude terpineol were obtained, representing a yield of 85.5% by weight based on the weight of the turpentine.

The terpineol content of the crude was 70%, or about 60% by weight on the weight of the turpentine.

Other concentrations of phosphoric acid may be employed as desired without departing from the scope of the invention.

As shown in this example, salts of the acid

catalysts employed other than sodium salts may be used if desired, though from the standpoint of economy it is usually preferred to form the alkaline solution with the use of soda ash.

Mixtures of sulphuric and phosphoric acids, as well as other acid catalysts may be used to excellent advantage, but as heretofore mentioned, we prefer to use sulphuric acid because of its relatively low cost.

10 The invention thus provides an economical process of a much reduced cycle of operations for producing greatly increased yields of partially refined terpineol from turpentine which may be further refined to any desired degree of purity by the well known vacuum fractionating processes.

Since certain obvious changes may be made in the details of the above procedures, in the acid catalysts employed and in the composition of the alkaline solution into which the turpentine-acid mixture is introduced without departing from the scope of the invention, it is intended that all the matter contained in the above description shall be interpreted as illustrative of the invention and not as a limitation thereto.

What we claim is:

1. The process of producing terpineol from turpentine comprising mixing turpentine in the weight ratio of one part thereof with about 1.08 to 2.88 parts of sulphuric acid bases of 100 percent at a concentration of about 60 percent and at a temperature of 0° to 5° C. to form a reaction therebetween, said reaction continuously producing crude terpinol hydrate dissolved in the acid mixture gradually up to maximum viscosity, introducing the mixture at its maximum viscosity directly into an alkali solution thus forming a slurry consisting of a free acid, terpinol hydrate and a concentrated aqueous salt solution, the free acid in the slurry being of the range of from approximately 0.7 N to 2.6 N, boiling the slurry to dehydrate the terpinol hydrate and form crude terpineol, and recovering the crude terpineol from the slurry.

2. The process as defined in and by claim 1 wherein the alkaline solution is formed from soda ash, and the concentrated aqueous solution is sodium sulphate.

3. The process of producing terpineol from turpentine comprising mixing turpentine in the weight ratio of one part thereof with about 1.08 to 2.88 parts of sulphuric acid basis of 100 percent at a concentration of about 55 to 65 per cent, at a temperature of 0° to 5° C. and within about 1½ hours to 3 hours to form a reaction therebetween, said reaction continuously producing crude terpinol hydrate dissolved in the acid mixture gradually up to maximum viscosity, introducing the mixture at its maximum viscosity directly into an alkali solution thus forming a slurry consisting of a free acid, terpinol hydrate and a concentrated aqueous salt solution, the free acid in the slurry being of the range of from approximately 0.7 N to 2.6 N, boiling the slurry to dehydrate the terpinol hydrate and form crude terpineol, and recovering the crude terpineol from the slurry.

4. The process as defined in and by claim 3 wherein the alkaline solution is formed from soda ash, and the concentrated aqueous solution is sodium sulphate.

5. The process of producing terpineol from turpentine comprising mixing turpentine in the weight ratio of one part thereof with about 1.08 to 2.88 parts of sulphuric acid basis of 100 percent at a concentration of about 60 per cent, at a temper-

11

ature of 0° to 5° C. and within about 1½ to 3 hours to form a reaction therebetween, said reaction continuously producing crude terpinol hydrate dissolved in the acid mixture gradually up to maximum viscosity, introducing the mixture gradually within a period of about 40 to 45 minutes, at its maximum viscosity directly into an alkali solution thus forming a slurry consisting of a free acid, terpinol hydrate and a concentrated aqueous salt solution, the free acid in the slurry being of the range of from approximately 0.7 N to 2.6 N, boiling the slurry to dehydrate the terpinol hydrate and form crude terpineol, and recovering the crude terpineol from the slurry.

6. The process as defined in and by claim 5 15

12

wherein the alkaline solution is formed from soda ash, and the concentrated aqueous solution is sodium sulphate.
